CLAIM

The ornamental design for a communications control
module, as shown and described.

DESCRIPTION

FIG. 1 is a top, front and right side perspective view of
a communications control module showing my new
design;

FIG. 2 is a top plan view thereof;

FIG. 3 is a bottom plan view thereof;

FIG. 4 is a side elevational view thereof, the opposite
side being a mirror image;

FIG. 5 is a front elevational view thereof; and,

FIG. 6 is a rear elevational view thereof.

FIG. 4.

FIG. 2.

FIG. 5.

FIG. 6.

FIG. 3.
